RAYMOND L. YOUNG, OF ST. LOUIS, MISSOURI, ASSIGNOR TO BEMIS BRO. BAG CO., OF ST. LOUIS, MISSOURI, A CORPORATION OF MISSOURI.

APPARATUS FOR AND METHOD OF SPLICING MULTIPLY THREAD.

Application filed February 12, 1926. Serial No. 87,750.

- My invention relates to improvements in apparatus for and method of splicing multiply thread, and has for its primary object the method of splicing the ends of multiply 5 threads together in such a manner that the splice of the threads is of substantially the same diameter as the remainder of the thread so that the same will readily pass through the eye of a sewing needle or looper.
- 10 A further object is to construct an apparatus whereby the plies of two threads can be untwisted and separated and then the separated plies tied together in such a manner that they will all be of the same length 15 with the knots of the plies separated longitudinally so that, upon the restoration of the twist to the separated plies, the spliced portion will be smooth.
- Heretofore in winding thread on cones or 20 spools a greater amount of thread was placed on the cone or spool than was on the bobbin which came from the twisting machine and in order to get the proper amount of thread on the cone or spool, it was necessary to use 25 several bobbins of thread, therefore when one bobbin was empty, another bobbin was employed and the loose ends either merely lapped over each other or else tied together in a square knot. In the instance of the 30 lapped ends, when these ends were reached in a sewing machine, the thread ran out of the eye of the needle or looper and necessitated rethreading, whereas with the square knot it was of such a size that it could not 35 pass through the needle or looper eye and consequently the thread had to be cut and rethreading was necessary. This caused a considerable waste of time as well as very often spoiling the work or necessitating the 40 ripping out of a sewed portion. By my improved method a cone or spool can be entirely run off and without any necessity of either cutting the thread or rethreading the needle.
- In the drawings:
- 45 Fig. 1 is a top plan view of my device showing the manner of separating the plies by untwisting and the manner of tying the same so that the tied plies will all be of the same length;
- 50 Fig. 2 is a side elevation of the same;
- Fig. 3 is an enlarged fragmental section of one of the untwisting drums;
- Fig. 4 is an end view of the same illustrating the manner of locking the thread 55 therein;
- Fig. 5 is an end view of the drum with the locked plate removed;
- Fig. 6 is a top plan view of the front and of the locking drum;
- Fig. 7 is an enlarged fragmental section 60 of one of the thread holding plates;
- Fig. 8 is a face view of the same;
- Fig. 9 is an enlarged side view of one of the guide posts employed;
- Fig. 10 is a top plan view of the same; 65
- Fig. 11 is an enlarged fragmental view of the upper end of one of the spacers;
- Fig. 12 is a diagrammatic view of a number of separated plies illustrating the manner in which the knots are spaced; and 70
- Fig. 13 is an enlarged view of a section of the thread including the splice.
- In the construction of my device, I employ a base 13. This base has considerable weight so that there will be no danger of the apparatus upsetting. The base 13 is mounted on swivel rollers 14 so that the device can be readily moved from place to place. Extending upward from the base is a column 15 which has a supporting member 16 secured to its upper end. Mounted on the supporting member 16 is a table 17. Secured to the underside of the table are bearings 18 in which a shaft 19 is rotatably mounted. The rear end of the shaft 19 is provided 80 with a handle or crank 20 by means of which the shaft can be rotated. Mounted on the shaft 19 and at its forward end is a gear 21. This gear extends through a slot 22 in the table. Mounted on the upper face of the 90 table and adjacent each side edge are supports 23 which have their upper ends open or slotted as at 24. The purpose of this will be explained in detail later.
- 95 Mounted in the bearings 23 are unwinding drums 25 which have gears 26^a located thereon. These gears are between adjacent bearings 23 and mesh with the gear 21 so that when the handle 20 is turned the unwinding drums will be rotated. The unwinding drums are each provided with a longitudinally extending slot or groove 26 of sufficient depth so that, when a thread lies therein, it will be below the bottom of the gear teeth of the gears 26^a so that there 105 will be no possibility of the thread coming in contact with the gears during their rotation. The unwinding drums have a portion of their ends cut away as indicated by the numeral 27. This cut away portion extends 110

slightly beyond the center of the drum, (see Figs. 5 and 6) leaving an extending portion 28. The extending portion 28 is provided with screw threaded bores 29 for the reception of screws 30 by means of which the plates 31 and 31^a can be attached to the unwinding drums. The plates 31 and 31^a are provided with a notch 32 which acts as a thread guide and which is in alignment with the slot 26 and also with a diametrically opposite slot 33. This slot extends radially and terminates adjacent the center or axis of the drum 25.

Carried by the top 17 and directly to the rear of the unwinding drums 25 are posts 34 on which are mounted thread holding plates 35 and 36. The thread holding plate 35 is fixed to its post by means of a pin so that it can not rotate, while the thread holding plate 36 is provided with a handle 37 so that it can be rotated. The handle 37 carries a stud 38 which passes through the support 34. It is also provided with a pin 39 which is adapted to enter a recess 40 in the rear of the support for holding the thread plate against rotation. The stud 38 is provided with a square portion 41 on which is mounted a disk or plate 42 and with a screw threaded portion 43. On this screw threaded portion is mounted a plate 44 which is held against independent rotation by means of a pin 45 which passes through the plates 42 and 44. The plate 44 is held in contact with the plate 42 by means of a coil spring 46 which surrounds the screw threaded portion 43 and which is pressed against the plate 45 by means of the screw threaded sleeve 47. The plate 48 of the thread holding plate 35 is held in position in a similar manner, that is it is held against rotation by means of a pin and also spring-pressed against the plate 35 in the same manner that the plate 44 is pressed. The plates 44 and 48 are each provided with a projecting lip 49 adjacent which is a slot 50, the purpose of which will be explained in detail later.

Mounted on the plate 17 and in alignment with and immediately to the rear of the unwinding drums 25 are posts 51, the upper end of which is broadened as at 52. This broadened portion is provided with a plurality of spaced slots 53 and are for the purpose of holding the plies of thread in separated position as illustrated in Fig. 1. Mounted on the plate are a plurality of guide posts 53^a, 54, 55 and 56. These posts are so arranged that when the various plies are tied, as illustrated in Fig. 1, the length of all the tied plies will be exactly the same. This is essential because, if the plies were not of equal length, it would be impossible to make a smooth splice. The upper end of each of the guide posts is round and tapered off as at 57. Extending through

the guide posts and projecting toward the rear of the machine are U shaped supports 58 which are for the purpose of supporting the threads and assuring that all will be tied at a point the same distance above the table top and practically in horizontal alignment with the thread as it issues from the rear of the unwinding drum. Each post is also provided with a spring 59 on its rear side which enters between the arms of the supports 58. This spring is for the purpose of holding the first knot tied in the plies and preventing it from slipping. Were this knot permitted to slip, it would be impossible to get all the tied plies the same length.

The operation of my device is as follows: 60 represents the cone which is being wound and 61 the bobbin as it comes from the twisting machine, 62 the thread leading from the cone and 63 the thread from the bobbin. When the ends of these threads are to be spliced, a predetermined amount of thread is drawn from both the bobbin 61 and cone 60. The ends of these threads are clamped or secured at the rear end of the table between the thread holding plates. The thread is then inserted in the slot at the rear of the untwisting drum and brought upward between the drum and plate 31^a, threaded and then passed through the slot 26, and then downward through the space 27. It is then brought around the solid portion 28 of the drum over the portion of the thread already in the slot 27 and upward through the slot 33 in the plate 31. In this way the portion 64 of each thread is tightly clamped and prevented from slipping. The handle 20 is then rotated in a direction so that the thread will be twisted in a direction opposite to the thread twist thereby untwisting the separate plies and permitting them to be separated. The separated plies are held in spaced apart position by means of the spacer. Should it occur that one of the threads untwists more readily than the other, the balance of the untwisting is taken care of by means of the handle 37 so that the plies of both threads can be readily separated. One ply from each thread is then broken loose adjacent the holding plates and without letting go of these plies, a single knot is tied and the ply thus tied with the single knot slipped over the post 58 until it rests on the support 58. The knot thus formed is held by the spring 59 against slipping and a second knot tied in the ply. A second ply is then broken loose from each of the threads and tied in a similar manner around the post 54, the next ply around the post 55, and the last ply around the post 56. Before tying these plies, however, they are removed from the spacer so that all of the plies will center at the plates 31^a secured at the rear of the untwisting drums. It will be noted that the posts 53^a, 54, 55 and 56 are arranged

on an ellipse, the focii of which are at 31^a. The purpose of this arrangement is to permit the plies when tied to be all of the same length. In other words the plies of the 5 threads when tied form two sides of a triangle, all of which sides are of equal length so that, when the thread, after being spliced, is straightened out, all of the plies are of equal length.

10 After the various plies have been thus tied and the ends cut off, they are removed from the posts, and the handle 20 rotated in the opposite direction thus taking out the twist which has been put into the threads 62 15 and 63 by untwisting the plies and restoring it to the tied plies. After this the thread is removed from the untwisting drums and the additional twist still remaining in threads 62 and 63, and equivalent to the 20 twist which was originally in that portion of the thread cut off after tying the respective ply knots, will automatically distribute and adjust itself throughout the length of the spliced portion. In this way it is believed on 25 account of the shortening of the thread that it will become more tightly twisted at the splice and thereby have a tendency to imbed the knots tied in separate plies in the plies adjacent to the knots. At all events, I have 30 discovered that a thread composed of a number of plies can be spliced by my method without materially increasing the size or diameter of the thread at the splice so that the splice will pass through the eye of a 35 sewing needle as readily as the remainder of the thread.

Another particular advantage of my method of splicing the thread is that not alone is the diameter of the thread at the 40 splice maintained substantially uniform but, by reason of staggering or separating the union between the various plies, the thread is not weakened at the splice nor is there any danger of the thread separating at the 45 splice for the reason that the connecting points of the various plies are so widely distributed relative to the diameter of the thread that they do not form a weak link in the chain.

50 It is to be understood, of course, that prior to removing the tied plies from the supports or guide posts, the free ends of the plies are trimmed short and fairly close to the knots so that there will be no long loose 55 ends sticking out from the thread after the plies have been twisted together.

The purpose of the drums 25 is primarily to serve as a means for carrying the thread past the pinions 26^a and in connection with 60 the plates 31 and 31^a present the threads 62 and 63 from being thrown into the meshes of the gears 26^a as these threads kink during the untwisting operation preparatory to splicing and, if these kinks were not held 65 away from the pinions, they would be drawn

into the gears and be cut or tangled therein. It is also obvious that my device can be used for splicing threads of any number of plies, it, of course, being necessary that the number of guide posts around which the un- 70 twisted plies are tied correspond in number to the plies of the thread to be spliced.

Having fully described my invention, what I claim is:

1. The method of splicing multiply 75 threads which consists in clamping the free ends of parallel spaced apart horizontally extending threads to prevent the same from untwisting, imparting to each thread at points equally removed from the application 80 of said clamping a rotary movement for removing the twist of said threads and to permit the plies thereof to be separated, arranging the plies of one thread in pairs with the plies of another thread, uniting by 85 individually tying together the pairs of plies at longitudinally spaced apart points without destroying the twist in the plies, partially restoring the twist in said threads, removing said threads at their point of 90 rotation, and, lastly, automatically restoring the remainder of the twist to the thread.

2. The method of splicing multiply 95 threads which consists in extending the end portions of two threads from separate sources of supply horizontally and in parallel relation to each other, holding the threads adjacent the ends thereof against rotation, imparting to each thread adjacent the source of supply and at points equally 100 removed from where the ends are held a rotary movement for removing the twist in said threads so as to permit the plies thereof to be separated, uniting by individually 105 tying together the plies of one thread to the plies of the other thread at longitudinally spaced apart points and without destroying the twist in said plies, and, lastly, removing said threads from their point of rotation and simultaneously and automatically 110 restoring the twist so removed to said plies.

3. The method of splicing multiply 115 threads which consists in clamping and holding at laterally spaced apart points the free ends of two horizontally parallel threads so as to prevent the same from rotating, simultaneously imparting to said threads at points equally removed from the application of said clamping a rotary movement for removing sufficient twist from the body of said threads to permit the plies thereof to be separated, uniting by individually 120 tying together the plies of one thread to the plies of the other thread so that the knots will be longitudinally spaced and the united plies be of equal length and, lastly, removing said threads from their rotating points and restoring the previously removed twist to the thread automatically. 125

4. The method of splicing multiply threads extending horizontally and parallel to each other and in the same direction, which consists in untwisting and separating the plies of equal lengths of the two threads, uniting the individual plies of one thread to the individual plies of the other thread without losing the twist in the individual plies so that the united plies will be of equal length and, lastly, removing said threads from their rotating points thereby automatically restoring the twist in the thread, which has been previously removed, so that the spliced portion will be more tightly twisted than the remainder of the thread.
5. The method of splicing multiply threads which consists in untwisting and separating the plies of equal lengths of two threads, uniting by tying the individual plies of one thread to the individual plies of the other thread without losing the twist in said threads so that the tied plies will be of equal length and the knots occasioned by such tying spaced longitudinally of the thread and, lastly, releasing said threads from their starting points thereby automatically restoring the twist in the thread whereby the spliced portion will have a twist slightly greater than the remainder of the thread.
6. The method of splicing multiply threads which consists in securing two parallel threads adjacent their ends, untwisting the plies of said threads for a predetermined portion adjacent the secured ends and simultaneously transferring the twist so taken out to adjacent untwisted portions of each thread, separating the plies of each untwisted portion, breaking one ply of each thread and tying said plies together without losing the twist therein, repeating the tying portion until all of said plies are secured together in such a manner that said pairs of plies are of equal length and with the knots uniting said plies longitudinally spaced, retwisting said plies together so as to partially return the twist previously removed, and then releasing said threads thereby permitting the twist transferred to the untwisted portion to automatically run into the spliced portion whereby said spliced portion becomes twisted tighter than the remainder of said thread.
7. The method of splicing multiply threads which consists in securing two horizontally parallel threads adjacent their ends against movement, untwisting a predetermined equal length of each of said threads adjacent their ends and simultaneously transferring said twist to an adjacent untwisted portion of each thread, separating the plies of the untwisted portion of each thread, breaking and tying one ply of one thread to a ply of the other thread and

without losing the twist in said plies and continuing the tying operation until all of the plies are united together in such a manner that all of said plies are of equal length and the knots joining said plies spaced longitudinally, trimming the ends of the plies adjacent the knots, partially restoring the twist to the tied plies, which has been previously removed, and then releasing said threads thereby permitting the remainder of the removed twist to automatically pass to the spliced portion whereby the spliced portion will be twisted tighter than the remainder of the thread.

8. An apparatus for multiply threads comprising a table, a roller support for said table, unwinding drums carried by and along one edge of said table, means for securing a thread to each of said drums, means for holding said threads adjacent their ends against rotation so that the same can be untwisted and the plies thereof separated, bifurcated means adjacent the unwinding drums for holding said plies in separated position, means carried by the table and located between the unwinding drums whereby the length of the plies and the position of the knots for securing the plies of the threads together is regulated, and means for rotating the unwinding drums in opposite directions for twisting and untwisting said threads, said threads adapted to be removed from the unwinding drums without returning the drums to their initial position.

9. An apparatus for splicing multiply threads comprising a table, means located at the rear of said table and adjacent each side for securing and holding the ends of threads against rotation, means located adjacent the forward edge of said plate and adapted to have the threads pass therethrough and be secured thereto, means for placing said last mentioned means in rotation whereby the thread between the first and second mentioned means is untwisted so that the plies can be separated, and spaced apart means carried by said table and adapted to act as guides so that the plies of one of the threads can be singly tied to the plies of the other thread and all of the plies when tied be of uniform length.

10. An apparatus for splicing multiply threads comprising a table, means located at the rear of said table and adjacent each side for holding the ends of two threads against rotation, means located adjacent the forward edge of said plate and adapted to have the threads pass therethrough and be secured thereto, means for placing said last mentioned means in rotation whereby the threads between the first and second mentioned means are untwisted so that the plies can be separated, spaced apart means carried by said table and adapted to act as guides so that the plies of one of the threads can be

singly tied to the plies of the other thread and all of the plies when tied be of uniform length, and means at the rear edge of said table whereby one of said threads can be 5 rotated so as to additionally untwist the plies thereof in the event the threads untwist unequally.

11. An apparatus for splicing multiply threads comprising a table, a support for 10 said table, unwinding drums carried by said table, means for securing a thread intermediate its ends to each of said drums, means for rotating said drums, means for securing and holding said threads adjacent one of 15 their ends against rotation so that the same can be untwisted and the plies thereof separated, means for holding said plies in separated position, spaced apart means elliptically arranged carried by the table whereby 20 the length of the plies and the position of the knots for securing the plies of the threads together is regulated, and means for equalizing the untwisting of said drums.

12. An apparatus for splicing multiply 25 threads comprising a table, a roller support for said table, unwinding drums rotatably carried by said table, a gear carried by each of said drums intermediate their ends, a driving gear carried by said table and meshing 30 with said drum gears for rotating said drums simultaneously, each of said drums being provided with a longitudinal slot so that a thread lying therein will be below the base of the gear teeth, means carried by the 35 ends of each of said drums for aligning and locking a thread carried thereby with the axis of rotation of said drums, means for rotating said driving gear, means for holding a portion of said threads against rotation 40 whereby the same can be untwisted and the plies separated, and means adjacent the unwinding drums for holding the plies in separated position.

13. An apparatus for splicing multiply 45 threads comprising a table, a support for said table, unwinding drums provided with a longitudinal slot rotatably carried by said table, gear teeth formed on said drums intermediate their ends, means located on the 50 end of each of said drums whereby a thread lying in said slot can be clamped, said means also centering the projecting portions of the thread with the axis of rotation of said drums, a gear wheel carried by said table 55 and meshing with the gear teeth on the drums for placing the same in rotation simultaneously, means for rotating said last mentioned gear, and means for holding one portion of said threads against rotation 60 whereby the same can be untwisted and the plies separated.

14. The apparatus of claim 13 in which supporting posts are provided by means of which the separated plies of one thread can

be individually tied to individual plies of another thread in such a manner that the tied plies will all be of equal length.

15. In a machine of the class described an unwinding drum composed of a cylindrical body provided with a longitudinal slot, a gear carried by said cylindrical body, and a slotted plate mounted against each end of said cylindrical body, a portion of each plate being spaced from the ends of said cylindrical body whereby a thread can be secured 75 to said cylindrical body and extend from each end thereof in alignment with the axis of the cylindrical body.

16. In a machine of the class described an unwinding drum composed of a cylindrical 80 body having gear teeth intermediate its ends and provided with a longitudinal slot of greater depth than the base of said teeth, a portion of each end of the drum being cut away so as to form a shoulder, and a slotted 85 plate secured again each end of said drum, said slot being out of alignment with the slot in the drum, and having its bottom coincident with the axis of the drum, whereby a thread is secured within said slot with its 90 ends projecting in alignment with the axis of the drum.

17. The method of splicing multiply threads which consist in holding the free ends of two separate sources of supply 95 against rotation, imparting to said threads at points equally removed from where they are held and intermediate the ends and the sources of supply a rotary movement for removing the twist from the threads between 100 the points of rotation and the ends so that the plies can be separated, and simultaneously therewith transferring the twist so removed to the portion of the threads between the points of rotation and the sources 105 of supply, separating the untwisted plies, tying one ply of one thread to a ply of the other thread without destroying the twist in the individual plies, continuing said tying operation till all of the plies of one 110 thread have been united to the plies of the other thread in such a manner that the knots at the points of tying will be longitudinally spaced apart and the combined length of the united plies be less than the combined length 115 of the original length of said plies, trimming the projected ends of the plies close to the knots, rotating the threads in the opposite direction for partially restoring a portion of the transferred twist to the spliced 120 portion, releasing said threads at their points of rotation, and, lastly, permitting the remainder of the transferred twist to distribute itself to the threads between the two sources of supply. 125

In testimony whereof I have affixed my signature.

RAYMOND L. YOUNG.
